UNITED STATES PATENT OFFICE.

JOSEPH THOMAS MOLLOY AND HARRY HEMPE, OF POUGHKEEPSIE, NEW YORK.

LATCH FOR AUTOMOBILE AND OTHER DOORS.

1,419,639.

Specification of Letters Patent. Patented June 13, 1922.

Application filed April 30, 1920. Serial No. 377,909.

To all whom it may concern:

Be it known that we, JOSEPH THOMAS MOLLOY and HARRY HEMPE, both citizens of the United States, and residents of Poughkeepsie, Dutchess County, New York, have invented certain new and useful Improvements in Latches for Automobile and other Doors; and we do hereby declare the following to be a full, clear, and exact description of the invention, such as will enable others skilled in the art to which it appertains to make and use the same.

This invention relates to door latches, particularly for automobiles.

The invention has for its object the provision of a latch of this character in which there are no projecting members on either side of the door when the door is closed to mar the appearance of the vehicle, and which may be caught in the clothing, with consequent damage thereto on accidental opening of the door.

A further object of the invention is to provide a latch of this character in which the door is held securely locked by a rigid bolt which can not be dislodged by jar or strain upon the door, but only when directly actuated for the purpose.

A further object of the invention is to provide a latch of this class in which the latch is released by a push button in the top of the door, which is readily accessible from either within or without the door by pressing the button below the top surface of the door, whereby the button may be easily actuated when desired to open the door, but cannot be accidentally opened by any pressure that may come on the door.

In the accompanying drawings we have illustrated our improved door latch designed for open cars with the push button in the supposed upper edge of the door, and also a modification thereof whereby the same form of latch may be used in closed cars with separate operating devices within and without the car.

In the accompanying drawings, Fig. 1 is a plan view looking down on the meeting edges of the door and the door jamb showing the parts of the latch in dotted lines;

Fig. 2 is a transverse sectional view on the line 2-2 of Fig. 3.

Fig. 3 is a longitudinal vertical section on line 3-3 of Fig. 2;

Figs. 4 and 5 are transverse vertical sec-

tions on lines 4-4 and 5-5, respectively of Fig. 2;

Fig. 6 is a detail view showing the end of the latch spindle in its casing; and

Fig. 7 is an elevational view partially in section on a reduced scale showing the application of the latch to closed cars.

Referring to the drawings, particularly to Fig. 1, 1 indicates the door jamb of the vehicle or other part to which the door is applied, and 2 indicates the door. A hole 3 is bored in the door parallel with its longitudinal edge, and seated in the hole 3 is a tubular casing 4 with its upper edge 70 flush with the top of the hole, but with its bottom clear of the bottom of the hole to allow an open space 5 beneath the casing.

Working in the casing 4 is a cylindrical push button 6 having a lower extension 7 in the form of a flat bar with a twist 8 in the bar near the bottom of the casing, the end of the bar projecting through a slot in the bottom wall of the casing. The end of the bar is provided with a pin or cotter 9 to prevent the button and bar being withdrawn from the casing, and a spring 10 within the casing and surrounding the bar, holds the button in its most elevated position as permitted by the pin or cotter 9. In such position the head of the button is above the surface of the upper edge of the door, in the manner shown in the drawings. The casing 4 is held in place in the door in any suitable manner, not shown, and is preferably inserted in the door before the door is assembled in its metal shell 11 so that the margin of the hole in the shell overlies the edge of the tubular casing, thereby providing a neat finish for the latch.

The twist in the bar 7 forms with the slot in the bottom of the casing a screw or spiral cam which has the effect of rotating the push button when it is depressed to thereby withdraw the latch 12, which consists of a rigid bar fixedly attached to the side of the push button and projecting through a slot in the side wall of the casing. The slot 13 in the casing is just the width of the bolt at its upper part, but at its lower end is withdrawn in the manner shown more particularly in Figs. 2 and 5 to permit a partial rotation of the latch when the button is pressed downward, the material of the door alongside the widened part of the slot being also cut away for this purpose.

To engage the latch bar 12 and hold the

door closed, we preferably provide a facing plate 14 on the door jamb having a slot 15 therein to receive the latch bar. An overlying plate 16 is fastened to the door jamb 5 on top of the plate 14 in the manner shown in Fig. 4, and this plate is provided with a spring tongue 17 having its edge spaced from the vertical edge 18 of the slot 15 by a distance equal to the width of the bolt, 10 whereby the latter will spring past the tongue 17 and be caught between the edge of the tongue and the edge 18 of the slot, thereby holding the door firmly latched. The meeting edges of the door jamb 2 and door 1 will preferably be inclined to the plane of the door to permit the end of the 15 bolt to reach the spring tongue when the door is slammed without leaving an edge opening in the door jamb, as will be evident 20 from Figs. 1 and 2.

The inclined portion of the slot 15 corresponds with the path taken by the edge of the bolt when the push button is depressed, to thereby turn the bolt toward the rear, or 25 inside, of the car to a sufficient extent for its end to clear the spring tongue 17 when the door is opened. The twist 8 in the bar 7 preferably terminates a little above the slot in the bottom wall of the tubular casing 4 30 so that the first depression of the button will not cause the latch to turn, but will press it straight down to a sufficient extent to clear the shoulder 18 of the slot in the face plate.

By this arrangement the bolt 18 which has 35 flat side faces, is held when the door is latched between the straight shoulder 18 of the slot and the straight edge of the spring stop 17, whereby the door will be held tightly latched and rattling prevented. The 40 chief cause of rattling in automobile doors when the ordinary beveled bolt is employed, is the tendency of the door to swing inward when through wear or distortion of the side of the car the space between the face of the 45 jamb and the edge of the door is enlarged.

With our improved square bolt working 50 between the square edges as described, the latch will not develop any lost motion by reason of the door pulling away from the jamb until it is pushed away sufficiently for the bolt to be free altogether.

Our improved bolt is particularly applicable to open cars as the flush push button forms not only a neat and inconspicuous 55 door control, but is much superior to the ordinary latches, projecting parts of which may be inadvertently caught and shifted to release the door when the car is in motion.

Our improved latch may, however, be applied with advantage to closed cars in the manner shown in Fig. 7. As here shown, the top of the button 6 is reduced to provide a swiveled connection with a cross bar 20 extending through a slot in the door and terminating in knobs or handles to be en-

gaged by the user. The door will be opened by thrusting straight down on the handle, thereby depressing the push button 6 and releasing the latch in the manner described, the other parts of the latch being identical 70 with the first described construction. This arrangement of operating device is safer than the ordinary style of handle which is shifted to one side to release the door as any push or pull against the door latch 75 through catching in the clothing is seldom directly downward.

We claim:

1. In a door latch, the combination with a door and its jamb of a latch-carrying 80 member mounted in one of said parts for longitudinal movement parallel with the meeting edges of said door and jamb, a bolt carried by said member adapted to engage a recess in the other part, and means for causing a rotation of said latch-carrying member by reason of its longitudinal movement to thereby effect a withdrawal of the bolt.

2. In a door latch, the combination with a door and its jamb of a latch-carrying member mounted in one of said parts for longitudinal movement parallel with the meeting edges of said door and jamb, a 90 bolt carried by said member adapted to engage a recess in the other part, means for causing a rotation of said latch-carrying member by reason of its longitudinal movement to thereby effect a withdrawal of the bolt, said means comprising a fixed guide 95 for said latch-carrying member and a spiral cam connection between said member and said fixed guide.

3. In a latch for automobile and other doors, the combination with the door and 105 its jamb of a bolt carried by one of said parts, said bolt being mounted for rotation about an axis parallel with the meeting faces of said door and jamb to effect the withdrawal of the bolt, and a shoulder carried by the other part for co-operation with 110 said bolt to hold the door latched, one of said engaging parts being mounted for independent movement away from the other so that the door may be latched without 115 rotating the bolt.

4. In a latch for automobile or other doors, the combination with the door and its jamb of a bolt carried by one of said parts, said bolt being mounted for rotation 120 about an axis parallel with the meeting faces of said door and jamb to effect the withdrawal of the bolt, and a member carried by the other part to be engaged by the bolt, said member having a resiliently 125 mounted part positioned to be thrust back by the pressure of the bolt when the door is closed, whereby the door may be latched without rotation of the bolt.

5. In a latch for vehicle and other doors, 130

- the combination with the door and its jamb of a bolt-carrying member mounted on one of said members for rotation about an axis parallel with the meeting edges of the door and the jamb and also for movement parallel to such axis, a cooperating piece carried by the other said part, said piece having a slot to receive said bolt, a part of said slot having a shoulder parallel with the axis of the bolt-carrying part and a transversely extending part whereby said bolt may be shifted axially to clear the shoulder and then turn transversely to withdraw the bolt clear of the jamb.
6. In a latch for vehicle and other doors, the combination with the door and its jamb of a bolt-carrying member mounted on one of said parts for movement in a direction parallel with the meeting faces of the door and jamb, a cam engaging said bolt-carrying member and arranged to effect a rotation of the bolt-carrying member upon its said movement, a cooperating piece carried by the other said part, said piece having a slot to receive said bolt, a part of said slot having a shoulder parallel with the axis of the bolt-carrying part and a transversely extending part whereby said bolt may be shifted axially to clear the shoulder and then turn transversely to withdraw the bolt clear of the jamb.
7. In a latch for vehicle and other doors, the combination with the door and its jamb of a bolt-carrying member mounted on one of said parts for movement in a direction parallel with the meeting faces of the door and jamb, a cam engaging said bolt-carrying member and arranged to effect a rotation of the bolt-carrying member upon its said movement, a cooperating piece carried by the other said part, said piece having a slot to receive said bolt, a part of said slot having a shoulder parallel with the axis of the bolt-carrying part and a transversely extending part whereby said bolt may be shifted axially to clear the shoulder and then turn transversely to withdraw the bolt clear of the jamb.
8. In combination with a door and jamb a latch bolt adapted to engage a recess in one of said parts, a member mounted in the other of said parts and movable parallel to the meeting edges of the parts, said bolt being carried by said member, and connections between said bolt and said member of such a nature as to impart to the bolt an up and down motion, upon actuation of said member in the aforesaid direction, for the purpose of withdrawing the latch-bolt from the recess.
- In testimony whereof we have hereunto affixed our signatures.

JOSEPH THOMAS MOLLOY.
HARRY HEMPE.
